UNITED STATES PATENT OFFICE.

MILTON C. MEYERFELD, OF SAN FRANCISCO, CALIFORNIA.

GARMENT-DISPLAYING DEVICE.

1,176,477.

Specification of Letters Patent. Patented Mar. 21, 1916.

Application filed April 26, 1915. Serial No. 23,958.

To all whom it may concern:

Be it known that I, MILTON C. MEYERFELD, a citizen of the United States, residing in the city and county of San Francisco and State of California, have invented new and useful Improvements in Garment-Displaying Devices, of which the following is a specification.

My invention relates to a method for conveniently supporting and displaying garments, and is particularly designed for the display of garments which may consist of a skirt and a waist, or like other constructions.

It consists of an elastic metal belt which can be expanded to fit the waist of the person, and in conjunction with this elastic belt are elastic holders carried by the belt and adapted to support the lower portion of the garment.

It also comprises details of construction which will be more fully explained by reference to the accompanying drawings, in which—

Figure 1 is a perspective view of the device. Fig. 2 is a rear perspective view showing a skirt supported by the device as in use.

In the fitting or sale of garments, and particularly of ladies' garments, it is often difficult where the garment is made in two parts, as for instance a waist and skirt, to obtain a proper fit and allow inspection of the goods in position to be examined. For instance, the waist may be put on and in order to show the effect of the waist with the skirt it is necessary to hold the skirt up with relation to the waist without actually putting it on, and my device is particularly intended for such display. It consists of an elastic band 2 of steel, left open at one side, as at 3, so that the ends can be separated to allow the band to be placed about the waist of the person upon whom the garment is to be tried. Fixed to the outside of this band are two segmental bands 4, the ends of which proximate to the open or separated ends of the band 2, are riveted or otherwise secured to said band. The opposite ends may be turned over, or otherwise finished, and approach each other at the opposite or closed side of the band 2, as shown at 5. The distance between these open ends of the exterior band and the rivets is such

that said bands may be freely separated to allow a garment or material to be introduced between these ends and the inner band. When the bands are released the garment will be held in position.

The operation will be as follows: In stores where ready-made garments are sold it often occurs that the purchaser will try on a waist which will be attractive, but by reason of the color would not look well with the skirt worn by the customer. The saleslady will then place the band around the waist of the purchaser with the separated ends of the springs 4 in front, then the skirt S which is intended to go with the waist can be introduced beneath these spring holders and adjusted up or down until it suits the height of the wearer and the fitter can then move away so that the purchaser can examine the skirt, or other material, in the mirror without interruption. It will thus be seen that the fitting and comparison of various skirts and waist can be easily effected without disrobing, and much time will be saved in trying on.

Having thus described my invention, what I claim and desire to secure by Letters Patent is—

A device for temporarily holding folded skirts onto the body of a person to display the skirt, composed of a split spring band adapted to encircle the waist line of the person, and a pair of springs carried by said band, each of said springs being secured at one end to the band adjacent the split portion thereof and extending around the band a distance less than half the length of the band, the opposite ends being free and relatively spaced apart to allow each of the sides of a folded skirt to be applied in the space between the free ends of the springs and moved to lie between the springs and band and to be thereby supported in draped position over the skirt of the person.

In testimony whereof I have hereunto set my hand in the presence of two subscribing witnesses.

MILTON C. MEYERFELD.
